(57) **CLAIM**

The ornamental design for a light diffuser, as shown and described.

DESCRIPTION

FIG. 1 is a perspective view of a light diffuser showing the new design;

FIG. 2 is a front view of the light diffuser as shown in FIG. 1;

FIG. 3 is a rear view of the light diffuser as shown in FIG. 1;

FIG. 4 is a right side view of the light diffuser as shown in FIG. 1;

FIG. 5 is a left side view of the light diffuser as shown in FIG. 1;

FIG. 6 is a top side view of the light diffuser as shown in FIG. 1;

FIG. 7 is a bottom view of the light diffuser as shown in FIG. 1; and,

FIG. 8 is a perspective view of the light diffuser inserted into an LED lighting channel.

The broken line showing the LED lighting channel depicts environment only and forms no part of the claimed design. The light diffuser is shown with a symbolic break in its length; the appearance of any portion of the article between the break lines forms no part of the claimed design.
